UNITED STATES PATENT OFFICE.

WILLIAM H. PRINZ, OF CHICAGO, ILLINOIS.

MALTING APPARATUS.

958,823.

Specification of Letters Patent. Patented May 24, 1910.

Application filed August 22, 1903. Serial No. 170,417.

To all whom it may concern:

Be it known that I, WILLIAM H. PRINZ, a citizen of the United States, residing at Chicago, in the county of Cook and State of Illinois, have invented certain new and useful Improvements in Malting Apparatus, of which the following is a specification, reference being had to the accompanying drawings.

10 My invention relates to apparatus for malting grain, and has to do particularly with malting-apparatus comprising a compartment-drum having an imperforate casting throughout, with means for supplying 15 attemperated air to the several compartments and distributing it uniformly throughout the grain therein, as described in my application for patent, Serial Number 170,416, filed August 22, 1903. In the apparatus illustrated 20 in my said application the fresh air is introduced into the malting-compartments axially, passing through the malt from the center toward the circumference and escaping from the compartments through perforated 25 conduits carried in the several compartments near the outer surfaces thereof,—said conduits communicating with an intermediate compartment. The foul air passes from the 30 said intermediate compartment to a suitable tunnel, which communicates with the mechanism—such as an exhaust fan—by which the circulation of air throughout the system is maintained; but, as explained in said application, the invention generically claimed 35 therein includes also the supplying of air to the compartments at the outer portions thereof and withdrawing it axially. My present invention in part involves the latter feature, but also has to do with certain other 40 features hereinafter pointed out. The apparatus employed is in many respects similar to the other,—differing principally in the arrangement of the flues by which fresh air is supplied to, and foul air conducted from, 45 the compartments.

In the accompanying drawings,—Figure 1 is a longitudinal vertical section of a drum embodying my improvements; Fig. 2 is a 50 horizontal view of the upper floor of a malt house, showing the arrangement of the attemperator, the fan and the flues leading to the different air-tunnels; and Fig. 3 is a horizontal section of the malting room.

55 Referring to the drawings,—A—B indicate malting-compartments, and C an intermediate compartment, which together

form the drum. It will be understood that the number of compartments may be varied as desired, and that an intermediate compartment C is provided between each pair of 60 malting-compartments A—B.

10—11 indicate the casings or shells of the compartments A, B, respectively, and 12 the casing of the compartment C. The shells 10—11 are secured at their inner ends to 65 heads 14—14, respectively, and at their outer ends to heads 15—16, respectively. The heads 13—14 are rigidly connected by a series of plates 17, as shown in Fig. 1.

18—19 indicate supports, which carry roll- 70 ers (not shown), on which the drum rotates,—annular rails 20 being provided at suitable points on the drum to engage said rollers, as described in my said application.

The shell 12 of compartment C does not 75 rotate,—being secured loosely at its edges between flanges 21—22 of the heads 13—14, respectively, as fully described in my application Serial Number 170,414, filed August 22, 1903. The ends of the shell 12 are 80 separated and fit closely around an air-conduit 23 at the bottom of the drum,—which conduit communicates with an air-tunnel 24, as shown in Fig. 1.

25—26 indicate conveyers, which receive 85 and carry off the grain from the drum-compartments,—suitable manholes being provided in the drum-casings for the discharge of the grain therefrom.

27—28 indicate perforated conduits, which 90 extend longitudinally of the compartments A—B and are concentrically disposed,—their ends being fitted in the heads of their respective compartments, as shown in Fig. 1. The inner ends of the conduits 27—28 are 95 closed by plates 29—30 securely fastened to the heads 13—14, respectively,—forming air-tight closures at those points.

31 indicates an air-conduit, which communicates through a T-connection 32 with 100 an external extension 33 of the conduit 27, as described in my former application, Serial Number 170,414.

34 indicates a conduit at the other end of the drum, which communicates through a 105 T-connection 35 with an extension 36 of the conduit 28,—the arrangement being such that the drum, with the extensions 33 and 36, may rotate freely, meanwhile being in communication with the conduits 31—34, 110 as described in my said application, Serial Number 170,414. The conduit 31 communi-

cates with an air-tunnel 37, and the conduit 34 with an air-tunnel 38.

39—40 indicate valves in the conduits 31—34, respectively.

5 41—42 indicate perforated conduits in the outer portions of the compartments A—B, respectively. The conduits 41—42 are secured in the heads of their respective compartments at short intervals, their inner 10 ends projecting through the heads 13—14, respectively, into the compartment C, as shown in Fig. 1,—thus communicating with the compartment C, so that fresh air in said compartment may enter said conduits and 15 by them be delivered to the compartments A—B, respectively, passing out through conduits 27—28 and the conduits 31—34 which communicate with them respectively. In this construction, the tunnel 24 is the fresh- 20 air tunnel, while the tunnels 37—38 are foul-air tunnels.

As explained in my application, Serial Number 170,416, during the process of malting the drum rotates slowly,—the result being 25 that the upper surface of the grain therein assumes an inclined position; consequently there are always some of the conduits 41—42 that are not covered by the grain in the compartments, and such uncovered conduits have their inner ends temporarily closed—thereby, for the time being, making them inoperative—by shields 43—44 secured to the casing 12 and overlying the inner ends of the exposed conduits 41—42, 30 as described in my said application.

45 indicates swinging cover-plates for the outer ends of the conduits 41—42, as shown in Fig. 1.

The drum may be rotated in any suitable 40 manner,—preferably by worms 46, operating in connection with worm-wheels 47, as described in the applications above referred to.

As best shown in Fig. 3, a series of drums 45 are arranged side by side in the malting room D—which is preferably on the lower floor of the malt house—and the tunnels 37—38 extend longitudinally of the malt house under said malting room, as indicated 50 by dotted lines in Fig. 3.

48—49 indicate flues, which communicate, respectively, with the tunnels 37—38, and terminate in a room E containing an exhaust fan 50, by which air is exhausted from 55 said flues and the tunnels 37—38.

F indicates the attemperator room, which communicates with tunnel 24 by means of a flue 51, as shown in Figs. 2 and 3. Suitable valves are provided for all of said flues.

60 52 indicates the attemperator, which is preferably of the construction described in my application Serial Number 170,414, and is placed between the upper end of the flue 51 and air-inlets 53—54. By this construction, fresh air passes from the attemperator

down through flue 51 to tunnel 24, thence passing up through conduit 23 to compartment C, where it enters the lower conduits 41—42, by them being distributed lengthwise of the compartments A—B at the outer 70 portions thereof. The air passes through the malt toward the center of the compartments, and escapes through conduits 27—28 and tunnels 37—38 which communicate with them,—thus providing inwardly-flowing 75 currents of air for ventilating the grain. It will be noted that the general direction of the air in both compartments is from the inner end portions thereof outward, so that the air flows in opposite directions in adjacent compartments, consequently the foul air from one compartment does not mingle with the fresh air going to the other compartment.

By placing a pressure-fan in the attemperator room the circulation of the air in the manner described may be effected by pressure, instead of by suction; and my invention includes either arrangement. Moreover, my invention is not restricted to the 90 specific details of the construction described, except in so far as they are particularly claimed.

That which I claim as my invention and desire to secure by Letters Patent is,— 95

1. A malting apparatus, comprising a plurality of rotary imperforate malting compartments arranged coaxially, means connecting said compartments so that they rotate in unison, and means communicating 100 with both ends of each of said compartments for directing fresh air through said compartments from the outer portions toward the axes thereof and toward opposite end portions of said compartments. 105

2. A malting apparatus, comprising a plurality of rotary imperforate malting compartments arranged coaxially, means connecting said compartments so that they rotate in unison, and means communicating 110 with both ends of each of said compartments for establishing a circulation of air through said compartments from the outer portions toward the axes thereof and from their inner end portions toward their outer 115 end portions.

3. A malting apparatus, comprising a plurality of rotary imperforate malting compartments arranged coaxially, means connecting said compartments together so that they rotate in unison, and means communicating with both ends of each of said compartments for directing fresh air through 120 said compartments in opposite directions.

4. A malting apparatus, comprising a plurality of rotary imperforate malting compartments, means connecting said compartments together so that they rotate in unison, means communicating with the inner 125 end portion of each of said compartments 130

for supplying fresh air thereto, means communicating with said compartments near the axes thereof for removing foul air therefrom, and means for preventing air from entering said compartments above the surface of the grain therein.

5. A malting apparatus, comprising a plurality of rotary imperforate malting compartments arranged coaxially, means connecting said compartments together so that they rotate in unison, means communicating with the inner end portions of each of said malting compartments near the peripheries thereof for supplying attenuated air thereto, and means communicating axially with the outer end portions of said compartments for conducting foul air therefrom.

10. A malting apparatus, comprising a plurality of rotary imperforate malting compartments arranged coaxially, a stationary intermediate compartment between adjacent malting compartments, means connecting said rotary compartments together so that they rotate in unison, means for rotating said malting compartments, and means communicating with the inner ends of said malting compartments for supplying attenuated air thereto.

15. A malting apparatus, comprising a stationary intermediate compartment, rotary malting compartments at opposite sides of said intermediate compartment, means connecting said rotary compartments together so that they rotate in unison, air conduits in the outer portions of said malting compartments, communicating with said intermediate compartment for supplying attenuated air to said malting compartments, and a central air conduit in each of said malting compartments for conducting foul air therefrom.

20. A malting apparatus, comprising a plurality of rotary imperforate malting compartments, perforated air conduits in said compartments near the peripheries thereof, means connecting said compartments together so that they rotate in unison, an intermediate compartment, the ends of said conduits communicating with said intermediate compartment, a separate air conduit communicating with said intermediate compartment, means for temporarily closing said first-mentioned conduits successively as said compartments rotate, means for rotating said malting compartments, and means for supplying fresh air to said intermediate compartment through said separate air conduit.

25. A malting apparatus, comprising a plurality of rotary imperforate malting compartments, perforated air conduits in said compartments near the peripheries thereof, means connecting said compartments together so that they rotate in unison, an intermediate compartment, the ends of said conduits communicating with said intermediate compartment, a separate air conduit communicating with said intermediate compartment, means for temporarily closing said first-mentioned conduits successively as said compartments rotate, means for rotating said malting compartments, and means for supplying fresh air to said intermediate compartment through said separate air conduit.

30. A malting apparatus, comprising a plurality of rotary imperforate malting compartments, perforated air conduits in said compartments near the peripheries thereof, means connecting said compartments together so that they rotate in unison, an intermediate compartment, the ends of said conduits communicating with said intermediate compartment, a separate air conduit communicating with said intermediate compartment, means for temporarily closing said first-mentioned conduits successively as said malting compartments rotate, means for rotating said malting compartments, and means for conducting foul air axially from said malting compartments.

35. A malting apparatus, comprising a plurality of rotary imperforate malting compartments, perforated air conduits in said compartments near the peripheries thereof, means connecting said compartments together so that they rotate in unison, an intermediate stationary compartment, the ends of said conduits communicating with said intermediate compartment, a separate air conduit communicating with said intermediate compartment, means for temporarily closing said first-mentioned conduits successively as said malting compartments rotate, means for rotating said malting compartments, and means for supplying fresh air to said intermediate compartment through said separate air conduit.

40. A malting apparatus, comprising a plurality of rotary malting compartments, an intermediate compartment between said malting compartments, means connecting said malting compartments together so that they rotate in unison, perforated air conduits in said malting compartments near the peripheries thereof, the inner ends of said perforated conduits extending into said intermediate compartment, stationary shields in the upper portion of said intermediate compartment for successively closing the projecting ends of said perforated conduits as the compartments rotate, means for supplying fresh attenuated air to said intermediate compartment, and means for conducting foul air from said malting compartments.

45. A malting apparatus, comprising a plurality of rotary imperforate malting compartments, an intermediate stationary compartment, means connecting said malting compartments together so that they rotate in unison, means for causing air from said intermediate compartment to flow inwardly through the malt in said malting compartments, and means communicating axially with said malting compartments for conducting foul air therefrom.
